CYLINDER GRINDING MACHINE

Charles A. Fulmer, Fort Thomas, Ky.

Application November 18, 1946, Serial No. 710,561

10 Claims. (Cl. 51—170)

1

This invention relates to grinding machines and is particularly directed to a machine for effecting special operations on "closed end" cylinders of aircraft motors, or the like.

The "closed end" cylinder has been in general use for some time in connection with internal combustion engines for aircraft, or the like. The bores of these cylinders are originally ground and honed to within minute tolerances and during use are subjected to intensive wearing actions by the reciprocation of the motor piston and piston rings therein. It is a well recognized fact that the stroke of a piston and its associated rings within a cylinder unequally wear away the internal, lateral surface of the cylinder bore until it is slightly elliptical in transverse cross section, the greater elliptical diameter being in the plane of movement of the associated piston connecting rod, or at right angles to the axis of the motor crankshaft. Also the piston rings do not traverse the entire lateral surface of the cylinder bore but have an upper limit of motion removed from the "closed end" of the cylinder. The portion of the internal lateral surface of a worn cylinder over which the piston rings travel has a much greater elliptical shape than the remainder of the cylinder surface thereby forming a ridge at the "closed end" thereof. The length of said ridge is determined by the distance between the top of the cylinder and the uppermost point of travel of the piston rings.

In providing motors with new rings without a cylinder regrinding operation, this ridge is objectionable in that new, unworn rings run against it during the first revolutions of the overhauled motor and cause breakage or damage to the top ring and/or damage to the motor. It is therefore the primary object of the invention to provide a machine for grinding off a substantially circular ridge from the elliptically shaped lateral face of a worn cylinder so that the ground section will substantially conform to the elliptical contour of the worn section of the face.

Another object of the invention is to provide a machine which makes obsolete the previous method of grinding off a cylinder ridge by a hand tool operation which required a great deal of time with little assurance for accuracy except that of the skill of a trained operator.

A further object of the invention is to provide an improved grinding machine of the character described which has a novel combination and arrangements of parts, is thoroughly reliable and efficient in operation, can be readily adjusted and set for grinding operations on all sizes of cylin-

ders, and is quickly and easily inserted into and withdrawn from the bores of said cylinders.

To the foregoing ends, generally stated, my invention consists of the novel devices and combination of devices, hereinafter described, illustrated in the drawing, and defined in the appended claims.

In the accompanying drawing which shows a preferred embodiment of my invention, like characters indicate like parts throughout the several views wherein:

Fig. 1 is a fragmental, side elevational view of my ridge grinding machine in operative position within a "closed end" cylinder.

Fig. 2 is a cross sectional view taken on line 2—2 of Fig. 1.

Fig. 3 is a cross sectional view taken on line 3—3 of Fig. 1.

Fig. 4 is an enlarged detail view of the depth stop means for my machine taken on line 4—4 of Fig. 2.

Fig. 5 is an enlarged detail view of the grinding wheel adjustment means.

Fig. 6 is a cross sectional view showing a modified form of the expansion roller mounting illustrated in Figs. 1—5.

In the drawings the numeral 10 denotes a frame or carriage adapted for rotary movement within a cylinder 11 for an internal combustion engine, or the like. The cylinder 11 has a "closed end" 12 having a suitable intake port 13 and an exhaust outlet port 14 formed therein. The usual cooling fins 15 are formed on the external lateral wall of the cylinder and said cylinder may also have a suitable motor block bolting flange 16 at its open end. In operative position the rings of a reciprocating piston traverse the internal lateral surface 17 of the cylinder throughout a substantial portion of its intermediate surface and after a period of use forms a circular ridge 18 thereon adjacent the "closed end." As illustrated in Fig. 2, the worn internal surface 17 of the cylinder has a slightly elliptical shape in transverse cross section and it is the particular function of my machine to grind the substantially circular ridge 18 so that it conforms to the elliptically shaped worn internal surface of the cylinder.

The carriage 10 is provided with two spaced lateral members 19 and 20 integrally joined together at their ends by cross webs 21 and 22 and provided with an intermediate cross web 23. The guiding means for the rotatable carriage within the cylinder comprises a pair of cylinder engaging wheels 24—24 and 25—25 rotatably fixed to

suitable arms extending from the side members 19 and 20 respectively. Each pair of wheels are disposed in spaced axial alignment on the axis which is parallel to the lateral face of the cylinder, and as most clearly illustrated in Fig. 2, the respective axes of the pairs of wheels are tangentially spaced a transverse angular distance which should be not greater than 90°.

The two pairs of wheels are urged into rolling contact with the worn lateral surface of the cylinder by means of a cylinder engaging pressure roller 26. This pressure roller is opposed to the pairs of wheels and has its axis lying on a bisector of the spaced pairs of wheels 24-24 and 25-25 which is perpendicular to the tangent extending between said wheels. As indicated in Figs. 1-5 the pressure roller is mounted for rotation on a lateral axle 27 parallel to the axes of the cylinder engaging wheels 24-24 and 25-25 and is supported between a pair of fork members 28 extending from a pneumatic piston 29. The piston is reciprocable and non-rotative within a pneumatic cylinder 30, integrally formed on the rear portion of the cross web 21, the movement of said piston within the cylinder being limited by a stop pin 31 threaded in the piston and radially movable in a slot 32 formed in the pneumatic cylinder wall. During operation of the machine air under pressure is supplied to the pneumatic cylinder by a flexible line 33 tapped into a flexible main air pressure line 34 by a suitable T connection 35.

A suitable compressed air motor 36 is rockably mounted between the members 19 and 20 of the carriage by suitable trunnions 37 and 38 which extend outwardly from a mounting bracket 39 surrounding the motor, said bracket being split at 40 and provided with suitable clamping nuts 41 (Fig. 3). The trunnions 37 and 38 have conical seats in their end faces which receive conical pivot pins 42 and 43 threaded in the members 19 and 20 respectively of the carriage and are secured therein by nuts 420 and 430 respectively. A grinding wheel 44 is fixed to a short drive shaft 45 of the motor, and as indicated in Fig. 2, the grinding wheel axis lies centrally between the pairs of cylinder engaging wheels 24-24 and 25-25 and is diametrically opposed to the pressure roller 26.

The shaft 45 of the motor is driven by compressed air introduced to the motor through the T connection 35. The exhaust ports 46 for the motor are directed toward the periphery of the grinding wheel as is clearly indicated in Fig. 1, the exhaust air being adapted to circulate about the wheel and carry off particles produced by the grinding operation through the cylinder ports 13 and 14. The main compressed air line 34 communicates with an air passageway 47 formed in the outer end of a handle 48 by a connection 49, said handle being threaded to the cross web 22 of the carriage and locked thereto by a set nut 50.

A depth stop is provided for the carriage to dispose the working face of the grinding wheel in transverse alignment with the circular ridge 18 to be ground from the cylinder, said stop being generally indicated by the reference numeral 51 and comprising a mushroom headed screw 52 threaded in a lug 53 and fixed therein by a set nut 54 (Fig. 4). The lug is provided with a pair of oppositely disposed and transversely extending mounting flanges 55 each having a vertical slot 56 formed therethrough, for receiving a countersunk set screw 57 which threadededly engages one of a plurality of internally threaded

bores 58 formed in the forward end 59 of the cross web 21. It will therefore be noted that the stop may be laterally and transversely extended for operation on various types of cylinders having different bore sizes.

An adjustable means is provided between the rockable motor and the carriage for adjusting the radial position of the grinding wheel, said means comprising a pair of spaced arms 60 depending from the motor mounting bracket 39 and embracing the head 61 of a boss 62. The head is pivoted between the arms 60 by a pin 63 secured therebetween and riding in a transverse slot 64 formed in the head 61. The boss 62 has a cylindrical portion provided with an internally threaded bore 65 for receiving the threaded end of an elongated adjusting screw 66. The boss is slidably supported within a close fitting bore 67 formed laterally through the cross web 23 of the carriage. As illustrated in Fig. 5, the adjusting screw 66 is rotatably mounted against axial movement in the cross web 22 by means of a thrust bearing 68 secured within an annular recess 69 in the web. The screw has an annular shoulder 70 formed thereon which abuts the inner race of the bearing 68, said inner race being secured to the shaft by a nut 71 threaded to said shaft and tightened against the race in the direction of said shoulder. The outer race is clamped against a shoulder 72 formed in the recess 69 by a ring 73 secured on the web 22 by screws 74. A suitable dial 75 is frictionally secured to the outer end 76 of the shaft 66 by an expansion spring 77 which encircles the shaft portion 76 and urges the dial against a collar 78 fixed to the shaft. The shaft is turned by a suitable hand wheel 79.

A modified form of pressure roller mounting for my device is illustrated in Fig. 6 wherein a piston 80 is disposed within the cylinder 81 extending radially from the carriage 21. The piston is urged outwardly by a compression spring 82 the limits of motion thereof being determined by the pin and slot arrangement 83 as in the preferred form of roller mounting illustrated in Figs. 1-5 inclusive. This modified roller mounting permits the use of an electric motor with my device instead of the pneumatic motor disclosed herein or it may be used in conjunction with a pneumatic motor, if desired.

In operation, the working face of the grinding wheel is first dressed on any suitable dressing mechanism to an angle which will leave the finished ground surface parallel to and flush with the lateral surface of the worn part of the cylinder. The grinding device is then inserted in the cylinder to be ground with the air motor inoperative and the grinding wheel is fed out radially by the hand wheel 79 until the wheel contacts the worn surface of the cylinder. In said position the dial 75 is rotated on shaft 76 into a zero position with respect to calibrations formed either on the dial or on the surface of the carriage surrounding said dial. The grinding wheel is then backed off a suitable distance from its finishing position by rotating the hand wheel 79, thereby rocking the motor on its trunnions and moving the grinding wheel a certain radial distance inwardly. The depth stop 51 is thereafter adjusted laterally and transversely for the particular cylinder to be ground and thereafter the entire machine is inserted through the open end of the cylinder until the stop 51 is against the cylinder head 12. Compressed air 75 is then introduced through the main line 34

which simultaneously expands the pneumatic cylinder for the pressure roller 26 and furnishes motive power for the grinding wheel. Upon introduction of air under pressure into the pneumatic cylinder 30, the pressure wheel 26 will expand outwardly and positively urge the two pairs of wheels 24-24 and 25-25 against the worn lateral surface of the cylinder. The pneumatic motor is thereafter rocked on its trunnions by rotation of the hand wheel 79 to feed the grinding wheel against the circular ridge 18 and the entire carriage is thereafter rotated by the handle 48 until a certain amount of stock has been ground from the entire circumference of the ridge. The hand wheel is again rotated to feed the grinding wheel a further distance into the work and again the handle 48 is rotated and said cycle of operations is continued until the indicator 75, by registering zero, shows that the proper amount of stock has been ground from the ridge.

What is claimed is:

1. In a cylinder grinding machine of the character described the combination of a rotatable carriage, spaced wheels fixed to the carriage and adapted to run on the internal lateral surface of the cylinder, a pressure roller opposed to the spaced wheels, a radially expandible roller mounting on the carriage, a motor having a short shaft, a grinding wheel fixed to the shaft, a transversely positioned trunnion means for mounting the motor to the carriage, and a means between the carriage and the motor for adjusting the radial position of the grinding wheel.

2. In a cylinder grinding machine of the character described the combination of a carriage rotatable within the cylinder, spaced wheels fixed to the carriage and adapted to run in a path around the internal, lateral surface of the cylinder, a pressure roller opposed to the spaced wheels, a radially expandible roller mounting on the carriage, and a motor driven grinding wheel mounted on the carriage for radial feeding movement with respect to the cylinder.

3. In a cylinder grinding machine of the character described the combination of a rotatable carriage, spaced wheels fixed to the carriage and adapted to run in a path on the internal, lateral surface of the cylinder, a cylinder engaging pressure roller opposed to the spaced wheels, a radially expandible roller mounting on the carriage, a motor having a short shaft extending laterally from the carriage end, a grinding wheel fixed to the shaft and positioned intermediate the lateral extensions of the wheels and in a position opposed to that of the pressure roller, a transverse trunnion for mounting the motor on the carriage, and adjustable means between the carriage and the motor for radially feeding the grinding wheel against the surface of the cylinder.

4. In a cylinder grinding machine of the character described the combination of a carriage rotatable within the cylinder, a pair of cylinder engaging wheels fixed to the carriage and disposed in spaced axial alignment on an axis parallel to the lateral face of the cylinder, a second pair of cylinder engaging wheels fixed to the carriage and positioned in spaced, axial alignment with their common axis parallel to the lateral face of the cylinder, said second pair of wheels being tangentially spaced from said first pair of wheels with respect to the cylinder surface, a cylinder engaging pressure roller opposed to the pairs of wheels, a radially expandible roller mounting on the carriage, and a motor driven

grinding wheel mounted on the carriage for urging the roller against the cylinder surface.

5. In a cylinder grinding machine of the character described the combination of a carriage rotatable within the cylinder, wheels fixed to the carriage and adapted to run in circular paths around the internal, lateral surface of the cylinder, said wheels being angularly spaced with respect to a transverse plane of the cylinder, a cylinder engaging pressure roller opposed to the wheels and having its axis lying on a diameter of the cylinder bisecting the angle between said wheels, a radially expandible roller mounting on the carriage, a motor driven grinding wheel diametrically opposed to the roller, trunnion means for mounting the grinding wheel on the carriage, and means between the trunnion means and the carriage for adjusting the radial position of the grinding wheel with respect to the cylinder surface.

6. In a cylinder grinding machine of the character described the combination of a carriage rotatable within the cylinder, a guiding means for the carriage within the cylinder comprising a pair of cylinder engaging wheels mounted on the carriage and disposed in spaced axial alignment on an axis parallel to the lateral face of the cylinder, a second pair of cylinder engaging wheels mounted on the carriage and relatively positioned in spaced axial alignment with their axes parallel to the said lateral face of the cylinder, the said second pair of wheels being tangentially spaced from said first pair of wheels, a cylinder engaging pressure roller opposed to the pairs of wheels and having its axis lying on a bisector of the spaced wheels perpendicular to the tangent extending between the said wheels, a radially expandible roller mounting on the carriage, a motor driven grinding wheel diametrically opposed to the roller, trunnion means for mounting the grinding wheel on the carriage, and means between the trunnion means and the carriage for adjusting the radial position of the grinding wheel with respect to the cylinder surface.

7. In a cylinder grinding machine of the character described the combination of a rotatable carriage, spaced wheels fixed to the carriage and adapted to run on the lateral surface of the cylinder, a cylinder engaging pressure roller opposed to the spaced wheels, a pneumatic cylinder for mounting the roller on the carriage for radial feed and return movement, a pneumatic motor having a short shaft extending laterally from the carriage end, a grinding wheel fixed to the shaft and positioned intermediate the lateral extensions of the wheel axes and diametrically opposed to the pressure roller position, air discharge outlets on the motor adapted to direct air laterally around the grinding wheel, a common source of compressed air for the motor and pneumatic cylinder, a transverse trunnion for mounting the motor on the carriage, and adjustable means between the carriage and the motor for radially feeding the grinding wheel against the surface of the cylinder.

8. In a cylinder grinding machine of the character described the combination of a rotatable carriage, spaced wheels fixed to the carriage and adapted to run on the lateral surface of the cylinder, a cylinder engaging pressure roller opposed to the spaced wheels, a pneumatic cylinder for mounting the roller on the carriage, a pneumatic motor rockably mounted on the carriage, a grinding wheel driven by the motor, air

outlets on the motor directed toward the grinding wheels, a common source of compressed air for the motor and pneumatic cylinder, and means between the carriage and motor for adjusting the radial position of the grinding wheel with respect to the cylinder surface.

9. In a ridge grinding machine for closed end cylinders the combination of a rotatable carriage, spaced wheels fixed to the carriage and adapted to run on the internal lateral surface of the cylinder, a pressure roller opposed to the position of the spaced wheels, a radially expansible roller mounting on the carriage, a motor driven grinding wheel mounted on the carriage for radial adjustment and having a working surface greater than the width of the ridge, and a depth stop laterally and transversely adjustable on the carriage and adapted to engage the "closed end" of the cylinder when the carriage is rotated within the cylinder.

10. In a cylinder grinding machine for grinding away the round ridge formed on the internal lateral surface of a worn cylinder for an internal

combustion engine, the combination of a carriage adapted for bodily insertion within the cylinder, a fixed wheel mounted on the carriage and adapted for rolling engagement around the said lateral surface, a transversely movable pressure roller mounted on the carriage in opposition to the fixed wheel and adapted for rolling engagement around the said lateral surface, a grinding wheel mounted on the carriage for transverse feeding movement against the ridge, and means fixed to the carriage and adapted for extension beyond the cylinder for rotating the carriage.
